UNITED STATES PATENT OFFICE.

JOHN GRAHAM, OF NEW YORK, N. Y.

DESIGN FOR GIMP.

SPECIFICATION forming part of Design No. 16,383, dated November 17, 1885.

Application filed March 25, 1885. Serial No. 160,139. Term of patent 7 years.

To all whom it may concern:

Be it known that I, JOHN GRAHAM, of New York, in the county of New York and State of New York, have invented a certain new and 5 original Design for Gimp, of which the following is a specification.

My design consists of pairs of bars of contrasting colors extending transversely to the length of the gimp, and U-shaped devices arranged at the ends of each pair of bars and opposite each other, one of the ends of each of these U-shaped devices extending against one of its adjacent pair of bars, and the other end against the other of said pair of bars.

15 The accompanying drawing is an enlarged face view of a piece of gimp embellished with my design.

A designates the body of the gimp. It has a feather edge, a; but this feature forms no 2c part of my design. Bars or bar-like devices b c extend transversely to the length of the gimp. They are grouped in pairs and are of contrasting colors. U-shaped devices d are

arranged at the ends of these bars or bar-like devices, opposite each other. One of the ends 25 of each of these U-shaped or bracket-shaped devices extends against one of its adjacent pair of bars, and the other end against the other of said pair of bars.

What I claim as my design, and desire to 30 secure by Letters Patent, is—

The design for gimp, consisting of pairs of bars of contrasting colors extending transversely to the length of the gimp, and U-shaped devices arranged at the ends of each 35 pair of bars and opposite each other, one of the ends of each of these U-shaped devices extending against one of its adjacent pair of bars, and the other end against the other of said pair of bars, substantially as shown and 40 described.

JOHN GRAHAM.
